GASOLINE PUMP INDICATOR HOUSING

Aquilles Alberto Correa De Sa E Benevides, Rio de Janeiro, Brazil, assignor to Texaco Brasil S.A.

Filed Sept. 28, 1973, Ser. No. 401,743

Term of patent 14 years

Int. Cl. D20—02

U.S. Cl. D52—2 A

FIG. 1 is a front elevational view of a gasoline pump indicator housing showing my new design, the rear being a mirror image thereto;

FIG. 2 is a top plan view thereof;

FIG. 3 is a right side elevational view thereof, the left side being identical thereto but with the handle omitted.

The rear and other end views are substantially the same as the front and end, respectively, since the unit is symmetrical.

I claim:

The ornamental design for a gasoline pump indicator housing, as shown and described.
